UNITED STATES PATENT OFFICE.

EDWARD ANDREW ZOBEL, OF HOLMESVILLE, NEBRASKA.

THREAD-SPOOL.

No. 904,396.

Specification of Letters Patent.

Patented Nov. 17, 1908.

Application filed December 24, 1907. Serial No. 407,938.

To all whom it may concern:

Be it known that I, EDWARD ANDREW ZOBEL, a citizen of the United States, residing at Holmesville, in the county of Gage and State of Nebraska, have invented a new and useful Improvement in Thread-Spools, of which the following is a specification.

My invention relates to an improvement in thread-spools and in carrying out the invention, I utilize what is usually a waste product, namely corn-cobs, which are particularly useful for the purpose in view of their great cheapness and the facility with which they may be worked up into the finished product.

In the accompanying drawing, Figure 1 is a view illustrating the division of a corn-cob into sections suitable for forming spool blanks. Fig. 2 is in part a side view and in part a longitudinal section of a spool blank, showing the manner of boring the same lengthwise. Fig. 3 is a side view (part being broken away) of the spool blank as it appears after the body or central part has been reduced and smoothed by removing the projecting fuzzy portion, and after cement has been applied to the bore. Fig. 4 is a cross section on line 4—4 of Fig. 3. Fig. 5 is a side view of the perfected spool, or as the blank appears after coating with a hard cement.

A corn-cob is first divided into sections 1, of the required length, and the next step consists in boring such sections centrally and longitudinally, this being done by a boring tool 2 as shown in Fig. 2. It is, however, manifest that the cob might be bored its whole length before division into sections.

The next step is cutting away, and thus removing, the soft fuzzy portion on the cylindrical body, or central part, of the spool blank, so that it presents the appearance shown in Fig. 3, the body being reduced in diameter and comparatively smooth, while the ends are left of full thickness and projecting readily beyond the middle 3. Then cement 5, of a variety that will adhere and harden to the required degree, is applied in the bore of the spool blank, so as to form a smooth interior coat of uniform thickness, which is necessary to adapt the finished spool for use on pins, spindles, or other similar supports. The last step is coating the entire spool blank with calcimine, which fills the cavities or interstices of the cob and forms a smooth hard coat 6 over the whole exterior, as shown by Fig. 5. This coat may be applied by dipping the blank in calcimine. The spool is then ready for use, and forms a cheaper, lighter, and durable substitute for the common wooden spool. A slit is formed in one of the enlarged ends of the spool to receive and hold the loose end of the thread.

What I claim is:

As a new and improved article of manufacture, the thread spool formed of a section of corn cob having a central bore, its body having a smaller diameter than the ends and the entire exterior having a smooth coat of calcimine, as shown and described.

EDWARD ANDREW ZOBEL.
